UNITED STATES PATENT OFFICE

104,128

DESIGN FOR A CHICKEN FRYER OR SIMILAR ARTICLE

Nicholas Abrams, Chicago, Ill.

Application December 11, 1936, Serial No. 66,480

Term of patent 14 years

To all whom it may concern:

Be it known that I, Nicholas Abrams, a citizen of the United States and resident of Chicago, in the county of Cook and State of Illinois, have invented a new, original, and ornamental Design for a Chicken Fryer or Similar Article, of which the following is a specification, reference being had to the accompanying drawing, forming a part thereof.

Fig. 1 is a view in perspective of a chicken fryer or similar article showing my new design; Fig. 2 is a top plan view of the same; and Fig. 3 is a side elevational view of the same, one side and the handle being shown broken away.

I claim:

The ornamental design for a chicken fryer or similar article substantially as shown.

NICHOLAS ABRAMS.
